UNITED STATES PATENT OFFICE.

JOHN Q. SHERMAN, OF DAYTON, OHIO.

MANIFOLDING MACHINE.

Application filed July 18, 1921. Serial No. 485,421.

To all whom it may concern:

Be it known that I, JOHN Q. SHERMAN, a citizen of the United States, and a resident of Dayton, in the county of Montgomery and State of Ohio, have invented certain new and useful Improvements in Manifolding Machines, of which the following is a full, clear, and exact description, reference being had to the accompanying drawings, 10 forming part of this specification.

My invention relates to manifolding machines and more particularly to means for feeding a plurality of copies of continuous webs of paper over a writing table 15 or platen whereupon said webs may be impressed or marked with copies of the same written or printed matter.

In connection with the feeding of paper through machines of the above general character, it is convenient to arrange the feed 20 operating devices so that one single operation thereof will withdraw the correct amount of paper for a single set of copies. In machines employing printed forms this 25 is particularly true, and one of the objects of my invention is to provide a manifolding machine wherein a single operation of the feed handle will feed through the machine one complete set of forms with the additional feature that the length of form may 30 be quickly and easily arranged for by a simple adjustment.

Thus my object is to produce an adjustable feed manifolding machine and it is 35 further to provide for aligning the webs of paper during a portion of the feed, and insuring just the correct engagement of the aligning devices which will serve to bring any desired number of webs into perfect 40 alignment utilizing for this purpose apertures formed in like positions in the paper.

Another object is to provide a novel 45 method of operating one or more feed pins, which will engage automatically in the paper and be drawn through a specially arranged path to both jog and feed the webs if desired. In addition to the feed pin operation I further propose to provide a paper clamping device and feed pin return 50 which co-operate to assure the correct position of the paper at all times.

In connection with the feed pin operation, 55 paper clamp and feed pin return it is my object to provide for adjustment at a single point to take care of not only the above three noted actions, but also the main paper

feeding parts, whereby the operator needs but make a single adjustment to bring all operating parts into correct position of readjustment with relation to the paper and 60 with relation to each other.

These objects and other advantages to be noted I accomplish by that certain construction and arrangement of parts to be herein-after more specifically pointed out and 65 claimed.

In the drawings—

Figure 1 is a side elevation, partly broken away, showing the novel feed device and indicating certain portions of an auto- 70 graphic register body.

Figure 2 is a plan view or detail showing the feed pin carrier device.

Figure 3 is an elevational detail showing one form of feed pin in side and plan view. 75

Figure 4 is a like view to Figure 3 showing another form of feed pin.

Figure 5 is a detail elevation of the end of the upper pressure roll.

Figure 6 is a plan view of the feed pin 80 engaging fork with a side view projected therefrom.

Figure 7 is an elevation of one of the feeding segment parts.

Figure 8 is an end elevation showing the 85 operating parts of the feed pin fork and latch mounted complete.

Figure 9 is a detail side and plan view of the latch for the feed pins.

Figure 10 is an end elevation showing the 90 paper clamp and its mounting.

Figure 11 is an end elevation showing the various adjustable cams and segments for operating the parts of the feed, together with the adjustable feature thereof. 95

Figure 12 is a plan view of the housing.

I have not shown any complete framework of a machine as any manifolding machine having a flat platen or writing table will serve the purpose. I have shown idler rollers 1 over which pass a plurality of webs of paper 2, said webs at some desired point for each form printed thereon having suitably placed holes cut therein for receiving the feed pins, to be later described, in a 100 fairly loose engagement.

Mounted on suitable lugs 3, on the side frame piece 4 of the machine, is the writing table 5, said writing table, in the example of the invention shown in the drawings, 110 being used as a support for the feed pin devices.

The main feed shaft 6 is revolvably mounted in the side frame pieces and directly above it the lid 7 of the machine houses a roller 8 which is suitably grooved 5 for feed pin clearance at 9. The shafts 10 and 11, mounted in brackets 12, 12, which are preferably mounted on the under side of the writing table, serve to mount the pin withdrawing and latching devices. The 10 shaft 13, suspended in brackets 14 from the writing table, serves to mount the paper clamp devices.

Of the lid or top 7 of the casing it should be noted that the housing 15 which carries 15 the friction roller 8 also is cut away with slots 16, 16, so as to provide clearance for the feed pin operation, said slots (Figure 12) being arranged in line with the grooves in the roller 8. Springs 17 bear on the spindle 20 of the said roller 8 to keep it down frictionally in the preferred form of the machine and the portion of the housing surrounding the slots 16 act to hold the paper steady at the point where the pins normally bear.

25 First describing the feed pin operation it will be noted that plates 18, 18, are secured on the under side of the writing table and so formed as to leave their adjacent edges 19 spaced away from the table, thereby 30 providing a slideway for a plate 20. This plate 20 is pulled rearwardly by means of a spring 21 until it abuts against a pair of stops 21^a set beneath the writing table.

At its forward edge the plate is provided 35 with arms 22, 22, each of which carries at its end a journal 23 for the shaft of a sliding pin. These journals or housings are partly closed at the bases to house springs 24, and extending forwardly from the housings 40 are fingers 25 which carry anti-friction rollers 26. Also extending still further forward from the rollers 26 are hooks 27.

The pins are formed with paper engaging 45 blunt tapered points 28 and shanks 29, said shanks terminating in reduced portions 30 and heads 31. When set into the journals or housings the heads are removed and the portions 30 thrust through the springs 24, after which the heads are secured in place. Since 50 the shanks fit the holes the pins may either revolve or slide in the journals.

The preferred forms of pins have small 55 gears cut in them above the shanks as at 32, and the points 28 may either be concentric with the gears as in the example shown in Figure 3 or eccentric, as shown in the example in Figure 4, the latter being the preferred form.

The guide plates 18, 18, which support the 60 sliding plate 20, are extended forward and cut with rack teeth 33, so that as the plate 20 is moved forward the pins will move along in a horizontal path with the springs 65 projecting them up through the writing table and also (Figure 4) will be given an

oscillating movement because of the action of the teeth 32 engaging with the teeth 33.

The writing table is slotted for pin clearance but as in Figure 1 the pins, when not in actual engagement with the paper, will 70 be held down by unpunched portions of paper lying above them on the writing table and will spring up into the holes in the paper as soon as registry therewith is established by the paper movement. As has been 75 noted, the extensions on the friction roller housing provide an abutment for the paper around the bearing point of the pins.

I provide adjustable segments for contact 80 with the friction roller 8 to accomplish the partial feed of the paper, and means controlled from the same shaft as the segments and adjustable with them for lowering the feed pins, latching the sliding plate 20 and subsequently releasing it as well as means 85 also controlled from said shaft for operating a paper clamp. This latter device operates just as the feed pins are withdrawn and while they are being unlatched and permitted to return to normal idle position. 90

The paper clamp, which I will next describe, comprises a finger or fingers 34, which are mounted on arms 35 on the shaft 13. An arm 36 on this shaft is pulled upwardly by means of a spring 37 to bring the 95 fingers up through holes 38 in the writing table and against the paper lying thereover, thereby clamping it between the said fingers and the portion 39 of the cover or top of the machine. 100

A controlling arm 40 on this shaft has an anti-friction roller 41 on its end which is held by the spring action on the shaft against a suitable cam (to be described) whereby the clamping position of the fingers is prevented except during desired periods of the feeding operation. 105

Coming next to describe the segment feed and the various controlling parts adjustable with the feed, it will be noted that on the main feed shaft 6 are an outer pair of fixed segments or if desired circular disks 42, which maintain a contact with the friction roller 8 and keep it from falling into a position to clamp the paper when the feeding segments have passed out of contact, although the roller could be arranged so that it cannot move far enough down to interfere. 115

Fixed on the shaft 6 just inside of the members 42 are a pair of fixed segments 43 which as the shaft is revolved come with their peripheries passing through slots in the writing table into contact with the paper as it lies against the friction roller 8, thereby feeding the paper. These segments, as shown, will be preferably a half circle or less. 120

A tubular shaft 44 is mounted on the shaft 6 and held adjustably thereon by means of set screws 45 operated by suitable winged 125

heads. This tubular shaft carries another pair of feeding segments 46 cut on the same arc as the segments 43, which also extend through the same slots, so that dependent upon the adjustment of the tubular shaft these segments will form extended feeding peripheries to the segments 43 or will simply lie alongside of them and serve to extend the width only of the combined feeding 10 periphery.

Also mounted on this tubular shaft are a pair of levers 47, which contact with the anti-friction rollers 26 alongside of the two feed pin journals and serve to force the said 15 journals along with the sliding plate 20 in a forward path.

The shaft 10, hitherto referred to, mounts a pair of forked arms 48, 48, which lie in the path of the lower ends of the feed pins, 20 so that as the levers 47 bring the pins forwardly the depending portions thereof ride into the forks. A spring 49 pulling on an arm 50 on this shaft 10 tends to keep the shaft in a position with the abutment piece 25 51 in contact with the brackets 12, while a roller 52, carried on an extension of said arm 50 in another direction, lies in the path of a cam 53 carried on the tubular shaft.

When the cam 53 contacts with this roller 30 it rocks the forks downwardly and thus pulls the feed pins down through their journals and holds them depressed until the cam has passed.

The shaft 11 on the brackets 12 carries a 35 pair of fixed hooks 54, 54, which engage the hooks 27 on the sliding plate arms, this action being controlled by a spring 55 pulling on the upward extension of a cross arm 56 on this shaft. The lower extension of this 40 arm lies in the path of a trip finger 57 on the tubular shaft 44, which, when it comes into contact position during the revolution of the feed shaft, will trip the hooks 54 and permit the sliding plate to spring rearwardly to its normal position.

Thus the positioning of the tubular shaft, once the various cams, trip fingers, and the like, are set permanently thereon, will adjust the length of the feeding operation of 50 the feed segments, adjust the period when the feed pins move forwardly, when they are depressed by the forks, and when they are released to spring back into normal position.

55 The cam 58 on the tubular shaft is the one that controls the paper clamp device, and its adjustment also will be controlled by the movement of the tubular shaft on the feed shaft 6.

60 Describing the entire operation of the machine: The operator sets his webs of paper over the writing table and beneath the friction roller with a good alignment of the forms duly arranged. He then revolves the handle 6^a of the feed shaft, after

releasing it from the stop 6^b and gives it a single revolution. This motion will first cause the feed segments through their contact with the paper under the friction roll to feed forward the desired amount of 70 paper. As the feeding peripheries pass from contact position, the levers 47 engage the pin carrier just after the pins are freed to spring up into the paper due to the registered holes therein coming into position 75 directly over the pin position. This accomplishes a forward feeding of the paper by the pins alone, and also a jogging or oscillation, which shakes down the webs onto the pins in a uniform position and compensates by shifting the webs of paper on themselves for inaccuracies in alignment.

As soon as the feed pins have been brought forward to a point when the levers 47 will pass out of engagement the forks 80 will pick up the pins and hold them steady while the latch device will have engaged the ends of the sliding plate arms. Then the cam device that controls the forks will rock the shaft 10 and depress the forks to 90 withdraw the pins from engagement with the holes in the paper.

When this depression has taken place the cam 58 will permit the paper clamp shaft to rock so as to bring its clamps into action 95 against the paper, after which the trip finger on the tubular shaft will strike the latch shaft around to depress the hooks thereon from engagement with the hooks on the ends of the plate arms. The forks will prevent the pins from rising into the holes in the paper until the plate has sprung back sufficient to clear said holes from the pins, after which the pins will rise to engagement with the under surface of the paper and will 100 be carried thus back to their normal position ready to spring up into another set of holes.

The completion of the single operation of the feed handle back to the stop 6^b will 110 complete a cycle, whereby the desired length web of paper has been fed and aligned and the alignment preserved during return of all parts. As shown in Figure 1 the corners of the outer feed segments at the close of the 115 operation will have just come to a position half way beneath the friction roller, thereby holding the paper against shifting while the machine is idle.

I have not attempted to describe or show 120 alternative structure, mechanically alike to those described, but do not wish this to be construed as a limitation of the claims that follow, since I have endeavored merely to show an exemplification of the invention as expressed in said claims.

Having thus described my invention, what I claim as new and desire to secure by Letters Patent, is:—

1. In a manifolding machine, the combi- 125

- nation with a friction feeding device for a plurality of webs of paper, of pin feeding means adapted to engage holes in the webs of paper and feed them through the machine, said means comprising a feed pin movable in the direction of feed, and simultaneously movable at angles to said direction to jog the paper, for the purpose described.
2. In a manifolding machine, the combination of friction means for feeding a plurality of webs of paper through the machine, and pin feeding means adapted to engage holes in the paper, said means comprising a feed pin, and means to move it in a path at right angles to its axis during a period of relaxation of the friction feed.
3. In a manifolding machine, the combination of friction means for feeding a plurality of webs of paper through the machine, a feed pin, to engage an aperture in said webs, and a carrier for said feed pin and means to operate said carrier so as to move it in a straight line in the path of said web.
4. In a manifolding machine, the combination of friction means for feeding a plurality of webs of paper through the machine, of a feed pin, means for axially moving it into and withdrawing it from holes in the paper, and means for moving it through a feeding path to draw the paper through the machine during a period of relaxation of the friction feed.
5. In a manifolding machine, the combination of friction means for feeding a plurality of webs of paper through the machine, of a feed pin, means for axially moving it into and withdrawing it from holes in the paper, and means for moving it through a feeding path to draw the paper through the machine during a period of relaxation of the friction feed, and simultaneously moving it at angles to the line of feed to jog the paper.
6. In a manifolding machine, the combination of friction means for feeding a plurality of webs of paper through the machine, of a feed pin, means for axially moving it into and withdrawing it from holes in the paper, and means for moving it through a feeding path to draw the paper through the machine during a period of relaxation of the friction feed, and a paper clamp to engage the paper during periods of no feeding either by friction or by the pin.
7. In a manifolding machine, the combination with a feed shaft, of an adjustable friction feed for a plurality of webs of paper adapted to feed such paper a desired distance at one complete operation of the shaft, a feed pin, means for supporting the pin so as to engage holes in the paper, same being independent of the friction feed, means on the feed shaft to operate the feed pin, said means having a common adjustability with the friction feed, whereby one adjustment
- accomplishes a setting of the friction feed and the pin operation.
8. In a manifolding machine, the combination with a feed shaft, of a friction feed for paper operated thereby, and having an adjustable feature to permit feeding of desired lengths of paper during individual rotations of the feed shaft, a feed pin, means for supporting the feed pin independently of the friction feed, means controlled by the shaft for operating the pin feed, a paper clamp to hold the paper against movement when neither pin nor friction feed is in operation, and common means for adjusting the timing of the pin and clamp operation together with the distance of feed of the friction feed, whereby a single adjustment accomplishes a setting of all three mechanisms for correct successive operation.
9. In a manifolding machine, a feed shaft, a friction feed and pin feed for a plurality of webs of paper, operative connection between said feeds and the shaft whereby they are successively operated from the said shaft to conjointly effectuate a feeding of a complete form from the machine, said pin feed having a feeding motion and a jogging motion, for the purpose described.
10. In a manifolding machine, the combination with a feed shaft, of a tubular shaft adjustable thereon, a friction feed disk having a segmental periphery and mounted on the feed shaft, another disk having a like periphery and mounted on the tubular shaft, a movable feed pin, means for supporting the pin so as to engage holes in the paper to be fed, and an operating member for said feed pin mounted on said tubular shaft, and means for adjusting the position of the tubular shaft with relation to the feed shaft, for the purpose described.
11. In a manifolding machine, the combination with a feed shaft, of another shaft co-axial therewith, a friction feed disk having a segmental periphery and mounted on the feed shaft, another disk of like nature mounted on the other shaft, a movable feed pin, means for supporting the pin so as to engage holes in the paper to be fed, and an operating member for said feed pin mounted on said other shaft, and means for adjusting the position of the other shaft to the feed shaft.
12. In a manifolding machine, a shaft, friction feeding means on said shaft for feeding paper during a portion of the revolution thereof, a feed pin, means for supporting the pin so as to engage holes in the said paper, means on said shaft for imparting a feeding movement to said pin during other portions of the revolution of said shaft, a revoluble operating member, and means for connecting said member to said shaft in a variety of positions, for the purpose described.

13. In a manifolding machine, a shaft, friction feeding means on said shaft for feeding paper during a portion of the revolution thereof, a feed pin, means for supporting the pin so as to engage holes in the said paper, means on said shaft for imparting a feeding movement to said pin during other portions of the revolution of said shaft, a revolute operating member, and means for connecting said member to said shaft in a variety of positions, and a feeding device for paper operated directly from the revolute operating member.

14. In a manifolding machine, a friction feed, a feed pin, a paper clamp, a common operating member for all of said mechanisms to cause an operation thereof in the order named, said friction feed having a rotary motion and said feed pin having a rectilinear motion.

15. In a manifolding machine, a friction feed, a feed pin, a paper clamp, a common operating member for all of said mechanisms to cause an operation thereof in the order named, said friction feed having a rotary motion and said feed pin having a rectilinear motion in a feeding direction, and an axial motion carrying it into and out of the paper, said common operator being adapted to provide for proper sequence in said pin motions.

16. In a manifolding machine, a friction feed, a feed pin, a paper clamp, a common operating member for all of said mechanisms to cause an operation thereof in the order named, said friction feed having a rotary motion and said feed pin having a rectilinear motion in a feeding direction, and an axial motion carrying it into and out of the paper, said common operator being adapted to provide for proper sequence in said pin motions, and a common adjustable member for adjusting the length of the friction feeding operation, and the relative timing of the feed pin operations.

17. A mechanism for operating a feed pin for feeding of a web of paper, comprising in combination with the feed shaft, a reciprocating member, means for resiliently housing a pin in said member, a pin depressing member, a detent for the reciprocating member, and means controlled by the feed shaft for operating the said reciprocating member, depressing member, and detent.

18. A mechanism for operating a feed pin for feeding of a web of paper, comprising in combination with the feed shaft, a reciprocating member, means for resiliently housing a pin in said member, a pin depressing member, a detent for the reciprocating member, and means controlled by the feed shaft for operating the said reciprocating member, depressing member, and detent, a paper clamp for engaging the paper during the period of movement of the reciprocating

member following a depression of the pin, and means on the feed shaft for controlling said clamp.

19. In a device for feeding a plurality of webs of apertured paper having a pin, means for supporting the pin so as to engage with said apertures, means for imparting a feeding path to said pin, means for imparting a thrusting and withdrawal motion to said pin with relation to the paper and means for causing the pin to travel in a wavy path during its feeding motion.

20. In a device of the character described, the combination with a reciprocating pin carrier, a pin carried therein, a feed shaft, connection from the feed shaft to the carrier, a pinion formed in connection with the said pin, and means for revolving the pinion and the pin during the movement of the carrier, said pin having an eccentric feeding point whereby an oscillating or wave-like motion will be imparted to the pin point during the movement of the carrier.

21. In a manifolding machine, the combination of a feed pin, means for supporting the pin so as to engage and to feed webs of paper over a writing surface, a carrier for said feed pin, said feed pin being revolutely mounted in the carrier, means for moving the carrier, means for revolving the pin, and an eccentric feeding point on said pin, for the purpose described.

22. In a manifolding machine a revolute feeding device having a broken periphery, a roll held toward said feeding device under tension, and means to revolve the feeding device to feed duplicate webs of paper between it and the roll, and means independent of the feeding device and operable while the broken portion of the periphery is turned toward the paper to align the paper webs.

23. In a manifolding machine, a revolute feeding device having a broken periphery, a roll held toward said feeding device under tension, and means to revolve the feeding device to feed duplicate webs of paper between it and the roll, and means independent of the feeding device and operable while the broken portion of the periphery is turned toward the paper to align the paper webs, said means comprising a pin to engage holes in the paper.

24. In a manifolding machine, a revolute feeding device having a broken periphery, a roll held toward said feeding device under tension, and means to revolve the feeding device to feed duplicate webs of paper between it and the roll, and means independent of the feeding device and operable while the broken portion of the periphery is turned toward the paper to align the paper webs, said means comprising a pin having a movement independent of the feeding device to engage holes in the paper.

25. In a manifolding machine, in combination a broken periphery rotary member, a co-operative member between which and the broken periphery member a plurality of webs of paper are fed upon contact with the unbroken periphery portions thereof, and means automatically operable to engage the paper during the remainder of the movement of the broken periphery member comprising a movable pin.
26. In a friction feed manifolding machine employing form strips with pin receiving holes therein, a pair of co-operative rotary members for feeding said strips, one of them having a portion of its periphery removed to cause a cessation of the friction feed, and a feed pin having a feeding movement and supported so as to engage the pin holes in the paper strips and feed them during the cessation of the friction feed.
27. In a friction feed manifolding machine employing form strips with pin receiving holes therein, a pair of co-operative rotary members for feeding said strips, one of them having a portion of its periphery removed to cause a cessation of the friction feed, and a feed pin having a feeding movement and means for supporting the pin so as to engage the pin holes in the paper strips and feed them during the cessation of the friction feed, said feed pin having an axial movement into the holes and a linear feeding movement.
28. In a friction feed manifolding machine employing form strips with pin receiving holes therein, a pair of co-operative rotary members for feeding said strips, one of them having a portion of its periphery removed to cause a cessation of the friction feed, and a feed pin having a feeding movement and means for supporting the pin so as to engage the pin holes in the paper strips and feed them during the cessation of the friction feed, said feed pin having an axial movement into the holes and a zig-zag linear movement for feeding and aligning the paper.

JOHN Q. SHERMAN.
